UNITED STATES PATENT OFFICE.

DAVID CABRERA LOPEZ, OF CHICAGO, ILLINOIS.

ENGINEER'S PROTRACTOR.

Application filed December 10, 1925. Serial No. 74,575.

This invention relates to improvements in engineers' protractors, and more particularly to improvements in the engineer's protractor forming the subject-matter of my copending application, filed May 16, 1925, serially numbered 30,850, and allowed February 23, 1927, and embodying a base, a limb adjustably connected to the base, and means which, while permitting the free adjustment 10 of the limb, is adapted to hold it against casual movement with respect to the base.

The present invention has for one of its objects the provision of novel and simple means through the medium of which the limb may be locked or positively secured against movement with respect to the base and which shall be adapted to be readily operated to either lock the limb to the base or free it for adjustment with respect 20 thereto.

A further object of the invention is the provision of a protractor of the character stated which shall include a rule slidably connected to the limb.

With the foregoing and other objects in view, the invention consists of the novel construction, combination and arrangement of parts hereinafter fully described and claimed, and illustrated in the accompanying drawing, wherein:

Figure 1 is an elevational view of an engineer's protractor constructed in accordance with the present invention.

Figure 2 is a detail sectional view taken on the plane indicated by the line 2—2 of Figure 1.

Figure 3 is a detail sectional view taken on the plane indicated by the line 3—3 of Figure 1, and

Figure 4 is a similar view taken on the plane indicated by the line 4—4 of Figure 1.

Corresponding and like parts are referred to in the following description, and designated in the several views of the accompanying drawing, by similar reference characters.

The protractor comprises a base 1 having angularly related straight edges 2 and 3 and provided with minute graduations 4. The base 1 is provided with an arcuate seat 5 for the arcuate edge 6 of the limb 7 which is preferably of semi-circular formation. The base 1 and limb 7 are connected to permit the latter to be adjusted with respect to the former, and this connection is established by means of a rib 8 which projects

from the seat 5 and fits in a groove 9 in the arcuate edge 6 of the limb. The limb 7 is provided with degree graduations 11. The rib 8 is provided in its lateral sides with grooves 8^a for the reception of projections 9^a extending inwardly from the side walls of the groove 9. Spring pressed plungers 12 carried by the base 1 and contacting with the limb 7, are adapted, while permitting the free adjustment of the limb, to hold it against casual movement.

The structure as far as described is embodied in my copending application. In accordance with the present invention, a friction block 13 carried by the rib 8 and contacting with the projections 9^a of the limb 7, is employed for the purpose of locking or positively securing the limb against movement with respect to the base 1. A rod 14 extending diagonally through the base 1 and connected at its inner end to the friction block 13, and a nut 15 threaded on the outer end of the rod and contacting with the base, constitute means by which the friction block may be adjusted to lock or release the limb 7. The lower outer corner of the base 1 is cut away as shown at 16, and it is against the inclined surface thus provided that the nut 15 rests. Furthermore, the cutting away of this corner of the base 1 permits the nut 15 to be confined wholly within the plane of the base.

The present invention contemplates mounting a rule 17 on the limb 7, and the rule is slidably connected to the straight edge of the limb by a dove-tail rib 18 formed on the rule and fitting in a similar groove 19 formed in said edge.

From the foregoing description, taken in connection with the accompanying drawing, it will be understood that the limb 7 may be readily adjusted with respect to the base 1, that the rule 17 may be readily adjusted with respect to the limb 7 and base 1, and that the limb 7 and rule 17 may be readily locked in adjusted position with respect to the base 1. To lock the limb 7 to the base 1 it is only necessary to turn the nut 15 onto the rod 14, and to release the limb it is only necessary to turn the nut 15 on the rod 14 in the reverse direction.

It should be understood that the drawing is merely illustrative and does not pretend to give exact proportions. Furthermore, the said drawing is illustrative of a preferred construction, it being my expectation that

various changes and modifications may be made without departing from the spirit and scope of my invention.

What is claimed is:—

- 5 An engineer's protractor comprising a base having angularly related straight edges and an arcuate seat, the lower outer corner of the base being cut away to provide an inclined surface and the base having an
- 10 opening extending from said surface to the seat, a rib formed on the seat and provided in the lateral sides thereof with grooves, a

limb provided with an arcuate groove receiving the rib and having projections on its side walls entering the grooves of the rib, 15 a friction block movably carried by the rib and contacting with the projections, a rod connected to the friction block and slidably mounted in the opening of the base, and a nut threaded on the rod and contacting with 20 the inclined surface of the base.

In testimony whereof I affix my signature.

DAVID CABRERA LOPEZ.
